US0D1031996S

(12) **United States Design Patent** (10) Patent No.: **US D1,031,996 S**
(45) Date of Patent: ** Jun. 18, 2024

(54) **BRAIN SENSING HEADSET**

(71) Applicant: **BrainSigns S.r.l.**, Rome (IT)

(72) Inventors: **Marika Aakesson**, Rome (IT);
Francesco Della Monica, Cava
de' Tirreni (IT)

(73) Assignee: **BrainSigns S.r.l.**, Rome (IT)

(**) Term: **15 Years**

(21) Appl. No.: **29/825,655**

(22) Filed: **Feb. 3, 2022**

(30) **Foreign Application Priority Data**

Aug. 4, 2021 (EM) 008641393-0001

(57) **CLAIM**

The ornamental design for a brain sensing headset, as shown and described.

DESCRIPTION

FIG. 1 is a top plan view of a brain sensing headset;
FIG. 2 is a bottom plan view thereof;
FIG. 3 is a front elevational view thereof;
FIG. 4 is a rear elevational view thereof;
FIG. 5 is a right side elevational view thereof (left side elevational view being a mirror image of the right side elevational view);
FIG. 6 is a front perspective view thereof; and,
FIG. 7 is a rear perspective view thereof.
The broken lines depict portions of the brain sensing headset that form no part of the claimed design.

1 Claim, 7 Drawing Sheets
